(57) **CLAIM**

The ornamental design for a toolbox with external compartment, as shown and described.

DESCRIPTION

FIG. 1 is a front elevational view of a toolbox with an external compartment according to the present invention; FIG. 2 is a rear elevational view thereof; FIG. 3 is a top plan view thereof; FIG. 4 is a bottom plan view thereof; FIG. 5 is a right side elevational view thereof, the left side view being a mirror image thereof; FIG. 6 is a perspective view thereof; FIG. 7 is a perspective view thereof showing the external compartment in an open position; FIG. 8 is a perspective view of the toolbox and of another external compartment mounted thereon; FIG. 9 is a perspective view similar to FIG. 8 showing the external compartment in an open position; FIG. 10 is a perspective view of the toolbox and of another external compartment mounted thereon; FIG. 11 is a perspective view similar to FIG. 10 showing the external compartment in an open position; FIG. 12 is a perspective view of the toolbox and of another external compartment mounted thereon; FIG. 13 is a perspective view similar to FIG. 12 showing the external compartment in an open position; and, FIG. 14 is a perspective view of the toolbox without an external compartment mounted thereon.
